ATTORNEYS.

UNITED STATES PATENT OFFICE

ALFONSE N. BECKER, OF MILWAUKEE, WISCONSIN, ASSIGNOR, BY MESNE ASSIGNMENTS, TO AUTOMATIC PARKING SYSTEMS, INC., A CORPORATION OF ILLINOIS

LEVELING DEVICE FOR CARRIERS

Application filed March 1, 1928. Serial No. 258,250.

This invention relates to improvements in leveling devices for carriers.

In the use of carriers, of both the lateral and vertical type, it has been found desirable to have a suitable means for bringing the carrier into exact registration with a floor or other landing point. One manner of accomplishing this object is described in applicant's pending application Ser. No. 222,105, now Patent No. 1,773,163, Aug. 19, 1930. The use in connection with a lateral carrier in a garage system is shown in application Ser. No. 241,884.

It is one of the objects of this invention to provide a leveling device for carriers in which a novel means is employed for absorbing the shock caused in making a landing.

It is a more specific object of this invention to provide a leveling device for carriers having an improved form of socket construction, in which the sides of the socket are adapted to yield in the direction in which the carrier is traveling.

It is a further object of this invention to provide an improved leveling device which is particularly well adapted for use upon carriers in garage systems.

It is a further object of this invention to provide a leveling device for carriers which is simple in construction and operation, and well adapted for the purpose described.

With the above and other objects in view, the invention consists of the improved leveling device, and all its parts and combinations, as set forth in the claims, and all equivalents thereof.

In the accompanying drawings, in which the same reference characters designate the same parts in all of the views:

Fig. 1 is a fragmentary plan view of a carrier and guideway, with the improved leveling device in connection therewith;

Fig. 2 is a sectional view taken on the line 2-2 of Fig. 1;

Fig. 3 is a detail plan view of the socket, parts being broken away, the dotted lines showing one side of the socket yielding to the pressure of the engaging member; and

Fig. 4 is a detail front view of the socket, parts being broken away.

Referring to the drawings, the numeral 8 designates a carrier which is positioned adjacent a guideway 9. The engaging mechanism comprises a suitable motor 10 mounted on the carrier. The motor drive shaft 11 extends outwardly, and is journaled within a bearing and housing 12. Within the housing, a gear wheel 13, mounted rigidly on the shaft, meshes with a larger gear 14 on a separate shaft 15. The latter gear in turn engages a gear 16 which is rigidly mounted on a shaft 17. One end of the shaft 17 extends through its bearing 18, and is formed with a worm 19 thereon. The worm is threaded in a threaded bore of a block 20, the latter having a pin 21 projecting from each side engaging side pieces 22. The side pieces are mounted at the inner end of a slid able member 23 which latter is adapted to move within grooves 24 of guiding members 25. At the outer end 70 of the slid able member, an extension 26 is riveted. The latter has a bore in its outer end, through which a pin 27, carrying an engaging wheel 28, extends.

Secured by suitable means to a plate 29 on the guideway, is a channel bar 30. Two spaced apart plates or inner socket members 31 extend transversely within said channel bar, and form a receptacle for the engaging wheel 28. A bolt 32 extends through the channel bar adjacent each socket member 31. An outer socket side piece 33 is pivoted at one end on each bolt 32, each side piece being formed at its inner end with a recessed extension 34 for engaging the rounded ends of the socket members 31 to prevent inward movement of the side pieces. The outer end of each side piece is curved outwardly. A pair of angular stop members 35, secured by rivets 36 to the edge of the guideway, are positioned adjacent the outer ends of the side pieces 33. The inner edge of the upward extension of each stop member is obliquely cut as at 37 to correspond to the end of the side piece 33, the cut being at such an angle as to permit outward movement of the side pieces.

Surrounding each bolt 32 is a coil spring 38, each of the latter having an end connected to the adjacent side pieces 33. These springs 100

normally maintain the side pieces in the position shown by the full lines in Fig. 3. When the side pieces are moved outwardly, as shown by the dotted lines, the movement is against the tension of the spring.

The operation of the device is as follows: When the carrier is approaching a landing point, the circuit to the motor 10 is automatically completed at a proper point, as fully explained and described in pending application Ser. No. 222,105. When this occurs, the worm 19 revolves and causes the engaging member to be threaded outwardly. As the carrier is sometimes moving at a considerable speed, it has been found desirable to provide means for absorbing the shock caused when the engaging wheel 28 enters the socket. For this reason, the yielding sides have been provided. As the wheel 28 strikes the side, as shown by the dotted lines in Fig. 3, the side piece will give against the tension of the spring and absorb the shock. At the same time the side piece will act to properly guide the engaging wheel into the space between the two plates or socket members 31, the final position of the engaging wheel being shown by the dotted lines in Fig. 1. As each side piece is yieldingly pivoted, the same effect will be produced in either direction of travel.

From the foregoing description it may be seen that the leveling device for carriers has a very novel form of socket, is simple in construction, and is well adapted for the purpose described.

What I claim is:

1. The combination with a carrier and a carrier guideway, of a leveling device therefor, comprising a socket member having pivoted, yielding sides, and an engaging member for engaging and disengaging said socket member when the carrier is at a landing point, one of said members being positioned on the carrier and one of said members being positioned on the guideway.

2. The combination with a carrier and a carrier guideway, of a leveling device therefor, comprising a pair of spaced apart socket side pieces, each side piece being pivoted at its inner end to the guideway, a stop member secured to the guideway adjacent the outer end of each side piece, an engaging member on the carrier for engaging and disengaging the socket member, and yielding means in connection with each socket side piece.

3. The combination with a carrier and a carrier guideway, of a leveling device therefor, comprising a pair of spaced apart plates on the guideway, a socket side piece for each plate, each side piece having its inner end pivoted adjacent its respective plate, a stop member fixed to the guideway adjacent each side piece, each stop member having an edge normally flush with the outer end of its respective side piece, an engaging member on the

carrier for engaging and disengaging the socket members, and yielding means in connection with each side piece.

4. The combination with a carrier and a carrier guideway, of a leveling device therefor, comprising a channel bar secured to the guideway, a pair of spaced apart plates transversely positioned within said channel bar, a bolt extending through the channel bar adjacent each plate, a socket side piece for each bolt, each side piece having its inner end pivoted to its respective bolt, a coil spring surrounding each bolt and having an end connected to the adjacent side piece, a stop member fixed to the guideway adjacent each side piece, each stop member having an edge normally flush with the outer end of its respective side piece, and an engaging member on the carrier for engaging and disengaging the socket members.

5. The combination with a carrier and a carrier guideway, of a leveling device therefor, comprising a pair of spaced apart guiding members on the carrier, an engaging member slidably between said guiding members, a block having a threaded bore therein mounted on said slidably engaging member, a worm shaft threaded in the bore of said block, a gear rigidly secured to said worm shaft, a driving motor, gear means connecting said motor with the gear on the worm shaft, and a socket on the guideway for engagement by said engaging member.

6. The combination with a carrier and a carrier guideway, of a leveling device therefor comprising an engaging member and a socket member, one of said members being positioned on the carrier and the other of said members being positioned on the guideway, said socket member having fixed inner side portions and having outer side portions, and yielding means in connection with said outer side portions to cause the latter to yieldingly guide the engaging member between the fixed inner side portions.

7. The combination with a carrier and a carrier guideway, of a leveling device therefor, comprising a socket member, and an engaging member for engaging and disengaging said socket member when the carrier is at a landing point, one of said members being positioned on the carrier and one of said members being positioned on the guideway, said socket having independently yielding side portions for yieldingly guiding the engaging member therein.

In testimony whereof, I affix my signature.
ALFONSE N. BECKER.
